Patented Dec. 23, 1890.

UNITED STATES PATENT OFFICE.

GEORGE H. REYNOLDS, OF NEW YORK, N. Y.

BOOK-FINISHER'S LETTERING-MACHINE.

SPECIFICATION forming part of Letters Patent No. 443,379, dated December 23, 1890.

Application filed May 29, 1890. Serial No. 353,572. (No model.)

To all whom it may concern:

Be it known that I, GEORGE H. REYNOLDS, of New York, in the county and State of New York, have invented a new and useful Book-Finishers' Lettering-Machine, of which the following is a full, clear, and exact description.

My invention relates to improvements in lettering-machines for book-finishing use; and the invention consists in certain features of construction and combination of parts, as hereinafter described, and indicated in the claims.

Reference is to be had to the accompanying drawings, forming a part of this specification, in which similar letters of reference indicate corresponding parts in all the figures.

Figure 1 is a front elevation of the machine with a pallet in position thereon. Fig. 2 is a side elevation with the front portion and base-plate in section, taken on the line 2 2 in Fig. 3. Fig. 3 is a plan view of the device. Fig. 4 is an enlarged broken partly-sectional elevation of the machine with the pallet removed, taken on the line 4 4 in Fig. 1. Fig. 5 is a perspective view of the pallet removed from the pressing-machine, and Fig. 6 is an enlarged detached view of a lettering-guide used in connection with the lettering-machine.

The base-plate A is preferably made rectangular in contour and level for the proper support of the article operated upon. Near the transverse center and at a suitable distance from the front edge *a* of the base-plate

35 A the vertical standard B is erected.

The standard B may be varied in form; but it is essential for the efficient action of the device that a forward projection of the standard be produced at a proper distance above the base-plate, thereby affording an arm B', whereon the working parts of the machine are supported.

On the forward portion of the arm B' there is a vertical housing-frame C formed or secured, which frame is laterally supported in connection with the arm of the standard by the web-braces *b*.

The vertical housing-frame C is constructed having opposite parallel guide-grooves *c* therein for the reception and support of a sliding head-block D, that is furnished with

laterally-extending tongues *d*, which loosely engage the grooves named, and thus retain the head-block in connection with the housing-frame C, free to reciprocate vertically 55 thereon.

As represented in Fig. 1, the head-block D is cut away to produce an aperture at *e*, which is preferably circular in shape, said aperture being intersected by a vertical slot cut from 60 the lower edge of the head-block, thus forming two depending limbs *g* on the head-block, which are of similar conformation, said limbs being provided for the adjustable retention of the pallet E in connection with the sliding head-block D, as will be further explained.

The head-block D is adjustably connected to the housing-frame C by a coarse-threaded screw *h*, which engages a nut or threaded orifice in the top wall of the frame, as at *i* in Fig. 2, and is loosely secured to the head-block in any suitable manner, so that a rotation of the screw by a manipulation of the hand-wheel *m*, that is affixed to the upper end of the screw, will slide the head-block D in the 75 grooves *c*, said hand-wheel having a diametrical size, which will afford required leverage in service.

Oppositely on the limbs *g* of the head-block D horizontal guide-ledges *n n'* are made to 80 project therefrom. The ledges *n* are located upon the exterior surface of the limbs *g*, and have their lower edges aligned with the lower edges of the limbs they are fastened upon. The inner ledges *n'* are made to extend a short 85 distance below the lower edges of the limbs *g*, and thus serve as an abutment for the pallet E. The upper edges of the inner ledges *n'* and outer ledges *n* lie in the same horizontal plane. Above the upper edges of the 90 ledges *n n'* guide-strips *o* are secured to the limbs *g*. Equal spaces intervene between each pair of the ledges and strips that are adjacent, so as to provide open guide-channels *o'*, wherein the hanger-loops *p* may be 95 introduced, as shown in Fig. 4.

The pallet or hand-tool E is of ordinary form, such as is used by book-binders in finishing the backs of bound books when these are to be lettered or ornamented by type-impressions.

As shown in Fig. 5, the tool E consists of

an elongated bar that is "L-shaped" in cross-section, there being a horizontal plate r , on one side edge of which an integral depending flange r' is formed, a handle s being attached 5 to the plate r at its center of length and width.

Two similar presser-blocks t are located on the lower face of the plate r and adapted to slide thereon by a dovetail engagement of 10 parts, (not shown,) the blocks t being adjusted longitudinally by the set-screws u , whereby they are caused to impinge against the series of type v , which are held in place laterally by the set-screw v' , which is inserted 15 through the depending ear v^2 and bears upon a binding-strip v^3 , that is located between the type v and ear v^2 , as shown in Figs 2 and 5.

Upon the inner surface of the head-block D a three-limbed brace w is attached thereto, 20 which brace stiffens the limbs y , and by the location of its vertical limb w' affords a guide for the proper introduction of the pallet E, the handle s of which pallet is made to align with this limb when the pallet is placed 25 in position between the limb g of the head-block D, which will correctly locate the type-holding frame of the pallet.

The hanger-loops p , Fig. 4, are formed of thin metal strips whose inwardly-bent and 30 aligned ends enter and are adapted to slide in guide-channels formed by and between the ledges n n' and strips o .

After the appropriate name or type ornamental design is assembled and secured in 35 the heated pallet-frame, then the pallet E is introduced between the limbs g , as previously explained, and there secured by sliding the loops p over the pallet-frame toward each other, as shown in Fig. 1, which will properly 40 dispose the lower faces of the types V to engage a book-cover or entire book placed under the head-block D, the distance or space between the base-plate A and the head-block D being such as will freely admit of the thickest 45 bound volume to lie between. If impressions are to be made on thin books, ribbons, bands, titles, &c., the work can be raised to the pallet E by being built from the base-plate A with blocks or boards surmounted by an iron 50 plate. When the book-cover has been correctly located below the pallet E, an impression is quickly and easily produced upon it by rotation of the hand-wheel m in a proper direction.

55 Ordinarily the workman can produce a design or name upon the book-cover without the use of a guide to locate the impression in a proper position on the book; but in some instances where accurate work requires such a 60 device the guide F may be employed with good results.

As represented, the guide F is composed of a flat bar x , from which two upright arms x'

project, which arms have an adjustable engagement within the keeper-loops x^2 , wherein 65 they may be slid, the thumb-screws x^3 serving to retain the guide-bar x at any point desired.

A parallel spacing-bar y is clamped upon the guide-bar x by set bolts and nuts y' , which 70 engage the slotted limbs y^2 of the spacing-bar, and by their adjustment retain the spacing-bar at any point advanced from the guide-bar.

In use, after the first line has been imprinted 75 upon a book-cover the spacing-bar, if set to indicate the proper space between lines, will by its edge designate where the book is to be placed, so as to align and space successive lines, which are to be impressed parallel to 80 the first or head line of the title, the vertical adjustment to suit books of different thicknesses being effected by sliding the bar y and its limbs y^2 in a vertical plane and securing the same where desired by a manipulation of 85 the set-screws x^3 .

Having thus described my invention, what I claim as new, and desire to secure by Letters Patent, is—

1. The combination, with the frame, of the 90 vertically-reciprocating head-block mounted thereon and having a central upwardly-extending slot or opening in its lower edge and front and rear guide-ribs along its lower edge at opposite sides of the slot, and pallet-carrying loops having inward-projecting upper ends to engage the said ribs, substantially as set forth.

2. The combination, with the frame, of the 95 vertically-reciprocating head-block having a central upward-extending slot or opening in its lower edge, opposite ribs on its front and rear sides along its lower edges, the lower edges of the rear ribs projecting below the lower edge of the head-block to form shoulders, and the pallet-carrying loops having inward-extending projections at their upper ends to engage the said ribs, substantially as set forth.

3. The combination, with the base having 100 an overhanging arm provided with a vertically-extending casing, and the vertically-reciprocating pallet-carrying head-block in said casing, of a vertically-adjustable gage comprising a cross-bar below and in front of the 105 head-block and provided with vertical arms adjustably secured to opposite ends of the casing, and a spacing-bar parallel with the said cross-bar and provided with slotted arms crossing said cross-bar and adjustable thereon to adjust the space between the said two bars, substantially as set forth.

GEO. H. REYNOLDS.
